UNITED STATES PATENT OFFICE.

FRANK L. BARROIS, OF NEW ORLEANS, LOUISIANA.

MAIL-BAG CATCHING AND DELIVERING APPARATUS.

1,113,595.

Specification of Letters Patent.

Patented Oct. 13, 1914.

Application filed March 3, 1914. Serial No. 822,231.

To all whom it may concern:

Be it known that I, FRANK L. BARROIS, a citizen of the United States of America, residing at New Orleans, in the parish of Orleans and State of Louisiana, have invented certain new and useful Improvements in Mail-Bag Catching and Delivering Apparatus, of which the following is a specification.

This invention relates to mail-bag catching and delivering apparatus, and it proposes, briefly, an improved device which acts both to initially support and to remove a bag, and which may be used with equal facility either on the mail-car or at the station, thereby obviating the necessity of parts of different construction, with a resultant decrease in the cost of manufacture and installation.

An embodiment of the invention is illustrated in the accompanying drawing, wherein:

Figure 1 is a perspective view, taken from the interior of the car and showing the two devices at the moment when the transfer of the bags is about to take place; and Figs. 2 and 3 are side and plan views, respectively, showing said devices just before such transfer.

The two devices afore-mentioned are indicated, generally, in said drawing by the reference letters A and B, A being the device mounted in the door-opening 1 of the car 2, and B the complementary device mounted on the post 3 located at the station 35 at the requisite distance from the track. In each instance, the device consists of a single element which is employed both to support the mail-bag to be removed therefrom, and to effect the transfer of the other bag thereto. They are designed for interchangeable use, as previously stated, and they are also so constructed as to permit them to operate with the same degree of efficiency irrespective of the direction in which 45 the car is moving, for which reasons the description of one device will apply, in the main, to both.

In the construction illustrated, which may be considered as embodying the form at present preferred, each element, or device constituted thereby, comprises a pair of bars 4 and 5 that bisect each other at right angles and are integrally or otherwise rigidly connected together at the point of crossing. In the case of the car-carried device A, the bar 4, which acts as the support there-

for, extends across the door opening and is rotatably mounted or journaled at its ends in socketed bearings 6 affixed to the sides of said opening. This bar occupies a horizontal position at all times, as will be understood, and forms the axis or fulcrum about which the other bar 5 rotates, the latter bar being likewise disposed horizontally when the transfer of the mail-bags is to be effected, in which position it projects in opposite directions through the door opening, its front arm extending toward the track and its rear arm into the interior of the car. Suitable means is provided for 65 removably holding bar 5 in its working position, above specified, or in any other desired position, the means shown consisting of a ratchet 7 fixed to one end of arm 4 and engaged by a gravity-pawl 8 pivoted to the adjacent side wall of the door opening.

The device B located at the station has a different mounting from the device A on the car, in that its support is constituted by the rear arm of the bar 5, which arm is rigidly fastened by staples 9, or the like, to a cap plate 10 affixed to the top of post 3, so that the said device is incapable of rotation or other movement. To 80 reach this device, an elevated platform 11, having a flight of steps 12 leading thereto, is provided.

The actual supporting and removal of the mail-bags are effected by means of a cross-bar 13 that is rigidly secured to the outer or front end of the bar 5 of each device, and, like the bar 4, which it parallels, is bisected at right angles by bar 5. These bars 13 are but very little shorter than the bars 4 and 95 are formed at their ends with rearwardly-facing seats 14 for engagement with the bag-holding rings 15. The rings, as shown, are approximately rectangular, and their lower members are formed at their rear ends with depending seats 16 from which the mail-bags are suspended, while their rear members are centrally offset to form lateral shoulders 17, best seen in Fig. 2, as a result of which construction the upper portion of each offset member is disposed in a plane in advance of the lower portion thereof. The latter portions of said members are designed for insertion in the seats 14, with the shoulders 17 extending across the upper faces of the bar ends, so that said shoulders may thus be regarded as center-

ing means for the rings. The portions just indicated are held in place by pairs of retaining springs 18 that extend in opposite directions along the rear faces of the bars 5 13, are fastened thereto at their inner ends, and project at their outer ends across the seats, so as to exert their pressure directly against the interposed rings. They are pulled away from the corresponding seats, 10 in order to insert or remove the rings, by means of suitable handles 19, with which their outer ends are equipped.

Each device is finally equipped with a pair of springs 20 which act primarily as buffers, but which also serve, to some extent, to assist the retaining springs 18 in holding the bag rings in place in the seats 14. These springs 20 are approximately L-shaped, and the bent terminals of their rear arms are fastened to the bars 4, while their front arms converge inwardly toward the bars 5 and bear at their terminals against the inner portions of the springs 18.

The operation is substantially as follows: 25 Assuming that the car is moving in the direction indicated by the arrow in Fig. 1, the bag to be transferred from the car to the device at the station is suspended from the rear arm of bar 13, the shouldered rear member of its ring 15 being engaged in the seat 14 in that arm, while the other bag is similarly suspended from the proper arm of the bar 13 of the station-located device. 30 As the car approaches the station-device, the front arm of the car-device bar 13 will pass through the ring carried by the station-device, and in like manner, the arm of the station-device-bar 13 which projects toward the approaching 35 car will pass through the ring of the car-device. As the car approaches closer to the station-device, the two rings will strike against the adjacent springs 20, which will flex inwardly toward the bars 5 and thus 40 not only absorb the greater part of the impact shock, as will be understood, but also permit the rings to pass by their free ends and slide along the arms of the bars 13 until striking against the bars 5, the spring 45 ends then returning to normal position and locking the rings against accidental removal. At the moment when the car-device actually 50 passes the station device, the rings are forcibly withdrawn from their seats 14, thus 55 completing the transfer. The pawl 8 is then released from engagement with ratchet

7, thereby unlocking the car-device and permitting its loaded bar 13 to swing downwardly and inwardly through the door opening 1 into the car. The bag caught by the 60 station device may be readily removed therefrom by simply flexing the proper spring 20 inwardly, no rotation or other movement of the device itself as a whole being necessary. 65

It is to be observed that the main working parts of each of the two devices present a somewhat T-shaped appearance, the bar 13 constituting the head of the T, and the bar 5 the stem thereof. The central bar 4 70 acts in both devices as the support for the buffer springs 20, and, in the case of the car-device, acts also as the support for the device itself or the means whereby it may be mounted. Owing to this formation, it 75 will be apparent that the same device may be used interchangeable either in the car or at the station, (with the exception that the car-device requires the addition of the pawl-and-ratchet lock), and will operate 80 with equal facility irrespective of the direction from which the car approaches the station.

I claim:—

1. The combination of a mail-bag catching and delivering member having a lateral arm which is provided with a terminal seat and with a retaining spring extending thereacross; and a bag-supporting ring having a portion thereof adapted for reception in said seat, and an offset centering and retaining shoulder adapted for engagement with the upper edge of the seat. 85

2. The combination of a mail-bag catching and delivering member having a lateral arm which is provided with a terminal seat and with a retaining spring extending thereacross; and a substantially-rectangular bag-supporting ring having its rear member formed intermediate its ends with a centering and retaining shoulder adapted for engagement with the upper edge of the seat, the portion of said rear member directly beneath said shoulder being adapted for insertion in said seat. 95

In testimony whereof I have hereunto set my hand in presence of two subscribing witnesses.

FRANK L. BARROIS.
